US00D996816S

(12) **United States Design Patent** (10) **Patent No.:** **US D996,816 S**
(45) **Date of Patent:** **** Aug. 29, 2023**

(54) **COMBINED ELECTRONICS TRAY AND CONTAINER**

(71) Applicant: **Yondr, Inc.**, Glendale, CA (US)

(72) Inventor: **Graham Dugoni**, San Francisco, CA (US)

(73) Assignee: **YONDR, INC.**, San Francisco, CA (US)

(**) Term: **15 Years**

(21) Appl. No.: **29/815,314**

(22) Filed: **Nov. 12, 2021**

(51) **LOC (14) Cl.** 03-01

(52) **U.S. Cl.**

USPC **D3/294**

(57) **CLAIM**

The ornamental design for a combined electronics tray and container, as shown and described.

DESCRIPTION

FIG. 1 is a top perspective view of a combined electronics tray and container according to the present design; FIG. 2 is a front view of the combined electronics tray and container according to the present design; FIG. 3 is a rear view of the combined electronics tray and container according to the present design; FIG. 4 is a left side view of the combined electronics tray and container according to the present design; FIG. 5 is a right side view of the combined electronics tray and container according to the present design; FIG. 6 is a top view of the combined electronics tray and container according to the present design; and, FIG. 7 is a bottom view of the combined electronics tray and container according to the present design.

The broken lines shown in the drawings are for the purpose of illustrating portions of the combined electronics tray and container that form no part of the claimed design.

1 Claim, 5 Drawing Sheets
